UNITED STATES PATENT OFFICE.

ALANSON P. BRUSH, OF DETROIT, MICHIGAN.

OVERHEAD VALVE MECHANISM FOR ENGINES.

1,188,405.

Specification of Letters Patent. Patented June 27, 1916.

Original application filed November 30, 1914, Serial No. 874,607. Divided and this application filed May 22, 1915. Serial No. 29,743.

To all whom it may concern:

Be it known that I, ALANSON P. BRUSH, a citizen of the United States, residing at Detroit, in the county of Wayne and State 5 of Michigan, have invented a certain new and useful Improvement in Overhead Valve Mechanism for Engines, of which the following is a full, clear, and exact description.

This invention relates to so-called overhead valve mechanism for engines, especially internal combustion engines. Such mechanism as heretofore used has included a puppet valve with an upwardly extended stem, a spring for moving the valve up to 10 its seat, a rocker which is pivoted between its ends, and which, at its ends, respectively engages the upper end of the puppet valve stem and the upper end of an endwise movable push rod. This push rod is actuated by 15 a cam on the cam shaft, which sometimes engages directly with the lower end of the push rod and sometimes with what is known as a tappet rod. When the tappet rod is used, its upper end engages with and supports the lower end of the push rod, so that 20 the two rods are in effect a single push rod. It is not customary to connect the upper end of the push rod with the rocker, or the rocker with the valve stem, because there must be 25 some lost motion between the parts of this train of valve operating mechanism. Sometimes this lost motion is referred to as a valve clearance. If this clearance or lost motion is too much or too little the valve action is 30 relatively unsatisfactory. Usually the push rod is made so that its length can be varied. In fact, one of the reasons for making this 35 push rod of two parts, as shown, is to facilitate the varying of the effective length of the 40 push rod.

There is a serious objection to the above mentioned construction, in so far as its adjustability is concerned, growing out of the fact that the adjustment can only be effected 45 when the engine is not running; and, also, because one can not determine whether the proper adjustment has been arrived at unless the engine is running. Therefore, any 50 person seeking to adjust this train of mechanism to cause proper valve clearance or lost motion, must alternately stop and start the engine until the proper adjustment is attained.

The principal object of the present inven-

tion is to enable a person to adjust a part of 55 this train of valve operating mechanism while the engine is running.

Other objects of the invention are to provide a more satisfactory rocker for the puppet valve; to provide means for insuring the 60 lubrication of the rocker fulcrum; to provide a fulcrum for said rocker that will allow the rocker to extend in any desired direction therefrom; and to generally improve 65 overhead valve mechanism.

The invention consists in the construction and combination of parts shown in the drawing and hereinafter described and pointed out definitely in the appended 70 claims.

In the drawings, Figure 1 is a vertical section of an internal combustion engine equipped with this invention; Fig. 2 is a detached plan view of the rocker; Fig. 3 is a sectional view thereof in the plane of line 75 3—3 on Fig. 2.

The engine, except for the valve operating mechanism, may be of any desired construction; and the valve mechanism itself may be of the usual construction except as to the 80 rocker and the manner of pivoting it.

Referring to the parts by reference characters, 10 represents a puppet valve having an upwardly extended stem 11, which valve is moved upward to its seat 13 by means of 85 a spring 12. 14 represents the cam shaft of said engine; and on this shaft are as many cams 15 as may be required.

16 represents the endwise movable valve push rod. In the construction shown this 90 is made of two parts, viz., the push rod proper, and a tappet rod 16^a, which is in effect a downward extension of the push rod. This tappet rod may carry a friction roller 18 which engages directly with the 95 associated cam, and it may have a socket 16^b in its upper end to receive the lower end of the push rod proper, whereby the two parts of the push rod are held in operative alinement.

20 represents a rocker, and, obviously, there must be a rocker for each valve and its associated valve push rod. Each rocker engages at one end with the top of the stem of its associated valve, and at its other end 105 it engages with the top of the associated valve push rod. The fulcrum for this rocker is about midway between its ends, and it is

so constructed that it may be adjusted while the rocker is in operation. In the specific construction shown, this rocker has in its upper surface, and about midway between its ends, a spherical socket 20^a. The fulcrum for this lever is a stud 21, which is adjustably fixed to an overhead support 22, and has a spherical lower end 21^b which fits in said spherical socket. In the specific construction shown, the part which supports this fulcrum is a cap 22, which is removably secured to the upper end of the engine over the valves. The stud 21 screws down through a threaded hole in this cap; and, as stated, its inner end engages in said spherical socket, while its upper end, being above the cap, affords means for turning it and thereby causing it to move up and down, as required. This stud forms a one-way bearing for the rocker, and it has several advantages over any other form of one-way bearing which might be substituted for it. It is obviously not an expensive bearing, nor does it require any expensive additions to the engine itself to enable it to be adjustably carried thereby. It, likewise, permits the rocker to extend in any required direction from the valve stem to the valve push rod,—that is to say, it need not extend in a vertical plane at right angles to the crank shaft, but may extend in an oblique direction thereto as it does when used with the multi-cylinder V-type internal combustion engine, which forms the subject matter of my application, Serial No. 874,607, filed Nov. 30, 1914, of which this application is a division. This fulcrum stud may be hollow, whereby it may serve as a lubricant well into which a lubricant may be put through its upper end; and in that event a cap 23 may be screwed onto the projecting end of said stud to keep out the dirt. In that event, also, one or more openings 21^b should be made through the spherical lower end of this stud through which lubricant may run directly onto the engaging surface of said stud and rocker.

It is to be noted that the rocker is approximately U-shaped in cross section. Because of this shape it is possible that the rocker shall be a sheet metal stamping. At the ends of the rocker the lower surfaces which engage the valve stem and push rod, respectively, should preferably be made convex, as shown.

In order that the rocker may not turn on the axis of the fulcrum stud, and so move out of engagement with the valve stem and push rod, a slot 20^d may be made through that end of the rocker which engages the push rod; and the upper end of the push rod may go through this slot. In that event the push rod should be formed with a flange 16^a a short distance below its end for the lower surface of the rocker to engage with.

Having described my invention, I claim:

1. In overhead valve mechanism for engines, the combination of a puppet valve having a stem, a valve rocker operator, a valve rocker which, adjacent its ends, engages said valve stem and rocker operator respectively, which rocker has between its ends an open top fulcrum recess, an overhead support, and a fulcrum piece having its lower end fitted to said fulcrum recess, which fulcrum piece is adjustably connected with said overhead support. 70

2. In overhead valve mechanism for engines, the combination of a spring actuated puppet valve having a stem, a valve push rod, a valve rocker which, adjacent its ends, engages said push rod and valve stem respectively, which rocker has in its top surface and between its ends an open top fulcrum recess, a fulcrum member, a support for said fulcrum member, and means to adjust said fulcrum member with respect to said support in a direction at right angles to a line connecting the two points at which the ends of said rocker contact respectively with the push rod and valve stem. 85

3. In overhead valve mechanism for engines, the combination of a spring actuated puppet valve having a stem, a push rod, a rocker which, adjacent its ends, engages said valve stem and push rod, and which has in its upper side an open top fulcrum recess between said ends, a removable cap for protecting said valve operating mechanism, and a fulcrum piece which is threaded through said cap and which extends downward therefrom into the fulcrum recess of said rocker. 100

4. In overhead valve mechanism for engines, the combination of a puppet valve having a stem, a spring for closing said valve, a rocker which has a spherical recess 10^a in its upper surface and which at one end engages the upper end of said valve stem, a spherical ended fulcrum stud which engages in said socket in the rocker, an overhead support with which said fulcrum stud is adjustably connected, and means for rocking said rocker. 110

5. In overhead valve mechanism for engines, the combination of a puppet valve having a stem, a spring for closing said valve, a rocker which at one end engages the upper end of said valve stem and has a spherical socket in its upper surface, a stud supporting member above said valve, a fulcrum stud which screws through said support and has a spherical lower end which engages in said spherical socket, and a push rod which engages the under side of the other end of said rocker. 115

6. In overhead valve mechanism, the combination of a puppet valve having a stem, a spring for closing said valve, a fulcrumed rocker which at one end engages the upper end of said stem and has a spherical socket in its upper surface, a fulcrum stud which 125

has a spherical end that engages in said spherical socket and contains a lubricant well and has a hole leading therefrom directly through the rocker-engaging spherical end of said stud, and a push rod for operating said rocket.

In testimony whereof, I hereunto affix

my signature in the presence of two witnesses.
